UNITED STATES PATENT OFFICE.

CHARLES E. RICE, OF LIVERMORE, KENTUCKY.

WATER-SUPPLY DEVICE FOR LOCOMOTIVE TENDERS.

Application filed July 5, 1922. Serial No. 573,028.

To all whom it may concern:

Be it known that I, CHARLES E. RICE, a citizen of the United States, resident of Livermore, in the county of McLean and 5 State of Kentucky, have made a certain new and useful Invention in Water-Supply Devices for Locomotive Tenders; and I declare the following to be a full, clear, and exact 10 description of the same, such as will enable others skilled in the art to which it appertains to make and use the invention, reference being had to the accompanying drawings, and to letters or figures of reference 15 marked thereon, which form a part of this specification.

Figure 1 is a side view of the invention.

Figure 2 is a plan view of the same.

Figure 3 is a section on the line 3—3 Figure 1 and showing a vertical sectional 20 view of the operating device carried by the railway train, the water supply receptacle being shown as raised and its spout as unfolded.

Figure 4 is a detail vertical section of the 25 water supply receptacle showing its spout as folded.

Figure 5 is a section on the line 5—5

Figure 4.

Figure 6 is a detail side view of a part of 30 the gearing.

Figure 7 is a detail vertical section of the operating plunger device showing the plunger in lowered position.

The invention has relation to water elevators, designed to supply the tenders of locomotives with water, and operated by the movement or power of the train itself in approaching the point of water supply, an object being to provide a durable, efficient 40 and economical means for the purpose that will not freeze in cold weather. Other objects will appear.

The invention consists in the novel construction and combinations of parts as hereininafter set forth.

In the accompanying drawings illustrating the invention, the numeral 1 designates a tower located adjacent to the railway track at the point where water supply is desired 50 and having mounted at the top thereof a pulley 2, a suspension rope 3 passing around said pulley and downwardly within the tower and within a well 4 over which the

said tower is located, a receptacle 5 being carried at the lower end of said rope or 55 cable, and being kept constantly filled with water, either through natural means, or the bucket could be kept filled with water by pumping the supply from a distance if necessary. The bucket so located at the bottom 60 of the well and kept filled with water is at a sufficient distance below ground to prevent danger of freezing of the water, and is of sufficient capacity to supply the tender of the locomotive with the proper amount of water 65 when raised to the top of the tower and emptied or discharged into the tender by the means now to be described.

The suspension rope or cable 3 for the said receptacle or bucket having passed over the 70 pulley 2 at the top of the tower passes downwardly again around a pulley 6 at or near the bottom of the tower, and around a pulley 7 near the pulley 6 and in the nature of a drum whereon the said cable will be wound 75 as the receptacle is raised.

The drum 7 has its shaft 8 laterally extended to the center of the railway track 9, and at its outer end is provided with a spur gear wheel or pinion 10, in mesh with a 80 larger spur gear wheel 11, the latter being suitably mounted below the said track at the central part thereof, and in mesh at the top thereof with a rack 12, the teeth of which project downwardly, said rack being 85 mounted for slidable movement centrally of the track in a suitable guideway, and extending longitudinally of and parallel with said track.

The engine or the tender (designated at 90 13^a and both being cars of the train) is provided with a plunger 13, normally held in raised position by a latch lever 14, having one arm thereof engaging a seat or recess 15 of the plunger, and upon release of said 95 latch, which may be conveniently effected by the foot of the fireman or engineer upon the other arm of said latch lever, the plunger will be at once thrust downwardly by its spring 16 to lowered position, wherein it is 100 adapted for engagement with a lug or projection 17 of the aforesaid rack, this release and movement of the plunger being effected just prior to the arrival of the engine or 105 tender at the point of water supply.

The plunger being brought into engage-

ment with the said lug or projection, the movement of the train will slide the rack 12 longitudinally of the track a sufficient distance to effect rotation of the spur gears 10 and 11 and of the pulley 7, to raise the receptacle 5 to the top of the tower. This receptacle is slideable in guides vertically and is provided with a spout extension 18 adapted to extend laterally over and discharge into the water tank of the tender in the usual way, this spout extension having a flexible connection 19 with the bottom of the said receptacle and in the movement of the receptacle vertically in said guides occupying a vertical position and sliding vertically with the receptacle, the guides providing for maintaining the spout extension in said position, until the receptacle arrives at the limit of its upward movement, when said spout extension will automatically fall to horizontal position as shown in Figure 3 and will discharge the contents of the receptacle into the water tank of the tender, the train remaining stationary during said discharge. 25 Of course should the train not stop with the tender in just the proper position, the said flexible connection will admit of the discharge spout being laterally moved by the guiding hands of the fireman or attendant to the proper discharge position. Or if it should be thought advisable, the spout extension may be provided with an outer valve or closure, operable to admit of the discharge of the water thereby only when the train 30 has been moved to bring the water tank of the tender in proper position relative to the spout extension.

The lug or block 17 with which the plunger engages is located directly opposite the tower and is engageable by trains going in either direction to slide the rack in one direction or the other, to thereby wind the cable in one direction or the other upon the drum 7, and raise the water receptacle as stated. The plunger is adapted to drop to position to properly engage the block or projection 17 of the slideable rack, but no lower. Upon the water receptacle being emptied of its contents as stated, the plunger will engage release block or cam 19 suitably located in the center of the track, and will be thereby pushed upwardly to normal position against the tension of its spring, and will then be reengaged automatically by its said latch, and thereby held in raised position until again released by the fireman or engineer.

In the drop of the water receptacle to lowered position, the spout extension will be automatically raised to vertical position and will slide downwardly in said position with said receptacle. The water receptacle is of suitable capacity to supply the tender with the proper quantity of water by a single discharge thereof.

In the fall of the water receptacle to lowered position at the bottom of the well following the escape of the lower end of the plunger from engagement with the lug or block 17, the spur gears 10 and 11 and the drum 7 will be rotated reversely, and will thereby return the rack 12 to its normal position with its projection 17 laterally opposite the tower. The pulley 6 has its shaft provided with a suitable governor.

It is obvious that the use of this invention will avoid the expense of the water tanks now in use, and the objectionable leakage of said tanks, and will prevent the freezing of the water supply in all cases.

In the case of wells of different depths, where the water supply receptacle is required to be raised different heights, the position of the lug 17 initially may be varied so that the gearing will be operated for a greater length of time. This would apply mainly to double track roads where the device is required to work only in one direction for each track. In the case of single track roads, or for double track roads if desired, the gearing may be varied to suit each case or depth of well, whereby a given operation of the lug 17 will give varying results as to the height the water receptacle is raised.

I claim:

1. In a water supply device for the tenders of locomotives, a vertically reciprocating receptacle having normally a lowered position below ground, and means operable by a car in its movement, adapted to raise said receptacle to a suitable height for said supply and including a winding drum, a cable attached to said receptacle and adapted to be wound upon said drum, a reciprocating rack having an operating connection with said drum, and a device carried by said car and operable at will to engage said rack.

2. In a water supply device for the tenders of locomotives, a vertically reciprocating receptacle having normally a lowered position below ground, and means operable by a car in its movement, adapted to raise said receptacle to a suitable height for said supply and including a winding drum, a cable attached to said receptacle and adapted to be wound upon said drum, a reciprocating rack having an operating connection with said drum, and a device carried by said car and depressible at will to engage said rack, the fall of said receptacle to normal position acting to restore the parts to normal position, and said rack being movable in either direction by the car to wind said cable upon said drum.

3. In a water supply device for the tenders of locomotives, a vertically reciprocating receptacle having normally a lowered position below ground, and means operable by a car adapted to raise said receptacle to

a suitable height for said supply and including a device operable in the passage of the train of cars in either direction and a depressible device carried by said car and 5 operable at the will of the engineer or fireman and adapted to engage said first named device.

In testimony whereof I affix my signature in presence of two witnesses.

CHARLES E. RICE.
